CENTRIFUGAL PUMP WITH DUAL IMPELLER

Oystein Jacobsen, Montgomery County, Ohio, assignor to The Duriron Company, Inc., Dayton, Ohio, a corporation of New York

Application September 12, 1938, Serial No. 229,470

3 Claims. (Cl. 103—115)

This invention relates to centrifugal pumps, and in particular, to such pumps for pumping corrosive fluids.

One object of this invention is to provide a centrifugal pump having means for preventing the flow of corrosive fluid along the drive shaft and through the packing thereof.

Another object is to provide a centrifugal pump having an impeller mounted on a shaft supported within a casing, this impeller having a dual pumping function, one consisting of pumping the main body of fluid from the pump intake chamber and the other consisting of pumping the leakage fluid from the chamber adjacent the packing so as to prevent the leakage of corrosive fluid along the shaft.

Another object is to provide a centrifugal pump having an impeller with dual sets of vanes, one set of vanes working on the centrifugal principle to pump one portion of fluid, the other set of vanes working upon the jet principle for pumping fluid from another portion of the casing.

Another object is to provide a centrifugal pump having a hollow impeller and vanes inclosing separate chambers within the impeller, one set of vane chambers opening into the pump intake chamber, the other set of vane chambers opening into a chamber adjacent the pump shaft packing.

Another object is to provide a centrifugal pump, as set forth in the preceding paragraph, wherein one set of vane chambers operates upon the centrifugal principle and the other set upon the jet principle, preferably set up by means of ports interconnecting the two sets of vane chambers.

Another object is to provide a centrifugal pump having a casing with an intake chamber and a hollow impeller mounted on a shaft, and having vanes separating the interior of the impeller into two sets of vane chambers, the vane chambers of one set being directly connected to the pump intake chamber, the other set of vane chambers being connected to a chamber communicating with the pump shaft packing and connected to the first set of vane chambers by means of restricted ports setting up a jet action to provide a pumping effect within the second set of vane chambers.

In the drawings:

Figure 1 is a central longitudinal section through a preferred embodiment of the pump of this invention, taken along the broken line 55 1—1 in Figure 2.

Figure 2 is a central cross section taken along the line 2—2 in Figure 1.

General arrangement

In general, the centrifugal pump of this invention is intended for the pumping of corrosive fluids, which in prior pumps have leaked along the shaft, past the shaft packing, and have thereby created great damage to the parts therebeyond. The present invention provides a hollow impeller with the vanes thereof dividing the interior of the impeller into two sets of vane chambers. The first set of vane chambers communicates directly with the intake chamber of the pump, whereas the second set of vane chambers communicates directly with a chamber in communication with the pump shaft packing. The second set of vane chambers, however, is connected to the first set by means of restricted ports. These ports set up a jet action within the second set of vane chambers, thereby providing a suction in the latter and a second pumping effect. The interiors of the vane chambers are preferably made to diverge outwardly with an approximately Venturi configuration.

Construction

Referring to the drawings in detail, Figure 1 shows a pump constructed according to the principles of the invention, and consisting of a casing 10 having an end plate 11 secured thereto by the clamping ring 12, with the packing 13 therebetween. Bolts 14 hold the clamping ring 12, the end plate 11 and the casing 10 in engagement with the pump support 15. The casing 10 (Figure 2) is of volute shape, having a discharge port 16 terminating in an enlarged outlet end 17 engaged by a clamping ring 18 for the securing thereto of a discharge conduit. Similarly, the end plate 11 is provided with an intake extension 19 with an intake chamber 20 containing vanes 21 for preventing the swirling of the fluid entering the pump. The outer end 22 of the intake extension 19 is enlarged, and engaged by a clamping ring 23 for the purpose of securing thereto an intake conduit. The lower end of the casing 10 is provided with a drainage extension 24 having a drainage port 25, closed by a plate 26 held in position by the U-bolt 27.

The casing 10, or volute as it is also called by hydraulic engineers, is provided with a stuffing box extension 28 containing a packing 29 surrounding the pump drive shaft 30. The latter is provided with a reduced diameter portion 31 having a hub 32 thereon, connected to and support-

ing the side plates 33 and 34 of the impeller, generally designated 35. Mounted between the side plates 33 and 34 are spirally directed vanes 36. These vanes divide the interior of the impeller into alternately arranged vane chambers 37 and 38, respectively. The vane chambers 37 (Figure 1) at their inner ends open into the intake passageways 39 communicating with the pump intake chamber 28, whereas the vane chambers 38 open through the passageways 40 into the leakage chamber 41 on the opposite side of the hub 32 from the pump intake chamber 28. Restricted ports 42 interconnect the vane chambers 38 and the impeller hub chamber 43 (Figure 1). The surfaces 44 and 45 of the hub chamber 43 and pump intake chamber 28 are curved in an axial direction to take care of the vena contracta effect and increase the efficiency of the pump. The impeller 35 is separated from the adjacent inner walls of the casing 10 and end plate 11 by spaces or gaps 46 and 47, respectively, these gaps being necessary to permit free rotation of the impeller 35.

Operation

In the operation of the pump of this invention the rotation of the shaft 30 causes the vanes 36, by their centrifugal action, to set up a suction in their intake passages 39 leading into the hub chamber 43, thereby pumping the main body of the fluid from the pump intake chamber 28 outwardly through the vane chambers 37, and into the volute chamber 48, thence out through the discharge passageway 16, into the discharge conduit. At the same time the jet effect of the ports 42 sets up a suction and pumping action within the vane chambers 38, thereby pumping fluid through the latter from the leakage chamber 41, through the passageways 40. The leakage fluid thus passes outwardly through the vane chambers 38 and is likewise discharged into the volute chamber 48, and continues through the discharge passageway 16, into the discharge conduit.

In this manner the vane chambers 37 are caused to pump the main body of the fluid from the pump intake chamber 28 by means of a centrifugal action, whereas the vane chambers 38 pump the leakage fluid from the leakage chamber 41 outwardly by means of the jet action arising from the effect of the ports 42. The leakage fluid in the leakage chamber 41, which would

otherwise tend to work its way along the shaft 30 and through the packing 29, into the other parts of the mechanism, is thus prevented from doing so, and is constantly being pumped out of the pump along with the main body of the fluid. It will be understood, of course, that the various parts of the pump are constructed of corrosion-resistant materials for resisting the corroding effects of the acids and other fluids handled by the pump.

It will be understood that I desire to comprehend within my invention such modifications as come within the scope of the claims and the invention.

Having thus fully described my invention, what I claim as new and desire to secure by Letters Patent is:

1. In a centrifugal pump, a casing, a rotary impeller in said casing, and hollow vanes in said impeller forming one set of chambers, the spaces between the vanes forming another set of chambers, said sets of chambers communicating respectively with the opposite sides of said impeller, said sets of chambers having interconnecting ports near the inner ends of said hollow vanes.

2. In a centrifugal pump, a casing, a rotary impeller in said casing, and hollow vanes in said impeller forming one set of chambers, the spaces between the vanes forming another set of chambers, said sets of chambers communicating respectively with the opposite sides of said impeller, said sets of chambers having interconnected ports of restricted diameters near the inner ends of said hollow vanes.

3. In a centrifugal pump, a casing, a shaft rotatably supported at one side of said casing and terminating within said casing, a packing disposed between said shaft and said casing, an impeller hub on said shaft, a pair of side plates spaced by hollow vanes and joined to said hub, said hollow vanes forming with said side plates one set of chambers, and the spaces between said vanes and said side plates forming another set of chambers, said sets of chambers opening respectively into spaces on opposite sides of said hub and having near the inner ends of said hollow vanes interconnecting ports which have a restricted diameter and extend through a portion of said hub.

OYSTEIN JACOBSEN.
